UNITED STATES PATENT OFFICE.

JULIAN BRONISLAW KUROWSKI, OF LONDON, ENGLAND.

DESIGN FOR A VENDING KIOSK.

Application filed December 18, 1925. Serial No. 15,779. Term of patent 14 years.

To all whom it may concern:

Be it known that I, JULIAN BRONISLAW KUROWSKI, a citizen of the State of Poland, residing at 2 Addison Gardens, London, Kingdom of England, have invented a new, original, and ornamental Design for Vending Kiosk, of which the following is a specification, reference being had to the accompanying drawing, forming part thereof.

I claim:

The ornamental design for a vending kiosk as shown.

In witness whereof I have hereunto signed my name this 3rd day of Dec., 1925.

JULIAN BRONISLAW KUROWSKI.
